[57] CLAIM

A new and ornamental design for a motorcycle foot peg, as shown and described.

DESCRIPTION

FIG. 1 is a view in perspective as seen from the top, side and one end of a “motorcycle foot peg” showing our new design; FIG. 2 is an end elevation as seen from the end shown in FIG. 1;

FIG. 3 is an end elevation as seen from the end opposite that shown in FIG. 2;

FIG. 4 is a view in top plan;

FIG. 5 is a side elevation as seen from bottom to top of FIG. 4;

FIG. 6 is a side elevation as seen from the side opposite that shown in FIG. 5; and,

FIG. 7 is a view in bottom plan.
